UNITED STATES PATENT OFFICE.

DONALD MCKNIGHT HEPBURN, OF PHILADELPHIA, PENNSYLVANIA.

DEVICE FOR INTRODUCING FLUIDS INTO THE CYLINDERS OF INTERNAL-COMBUSTION MOTORS.

Application filed December 12, 1921. Serial No. 521,899.

To all whom it may concern:

Be it known that I, DONALD MCKNIGHT HEPBURN, a citizen of the United States, and a resident of Philadelphia, in the county of Philadelphia and State of Pennsylvania, have invented certain new and useful Improvements in Devices for Introducing Fluids into the Cylinders of Internal-Combustion Motors, whereof the following is a specification, reference being had to the accompanying drawings.

My invention relates generally to devices useful in introducing fluids into internal combustion motors and more especially in injecting preparations in liquid form for removing carbon from within the cylinders.

As is well known, such fluids are most effective when introduced while the cylinders are still hot; but on account of the high volatility characteristic of these fluids, it has been heretofore a matter of difficulty in introducing them without waste and without danger of injury through forcible rejection or expulsion from the cylinders under back pressure generated in the course of rapid vaporization.

The paramount object of my invention is to make the introduction of such liquids possible without the difficulties and danger above pointed out.

How this desideratum may be obtained will become readily apparent from the detailed description of one or more typical embodiments of my invention which follows:

In the drawings, Fig. I, is an elevation of an injecting device of my invention in a very simple form and showing the manner in which it is used in injecting fluid into the cylinder of an internal combustion engine through a priming cock.

Fig. II, is a view similar to Fig. I, although somewhat more fragmentary, of a modified form of my invention in which I have shown a special means whereby the injecting device may be detachably secured to the priming cock.

Fig. III, is an elevation, directed more especially to the showing of the means aforesaid, as viewed from the right of Fig. II, and

Fig. IV, is a detail cross section taken along the plane indicated at IV—IV in Figs. II, and III.

Referring first to the embodiment of my

improved injecting device illustrated in Fig. I, it will be observed to be in the form of a syringe 1 which is preferably of a type wherein the fluid is expelled from a cylinder or barrel 2, through the instrumentality of a piston (not shown) actuated by a handle 3. The nozzle 4 of the syringe has secured to it about its end, a tapered tip 5 of a suitable resilient material, preferably rubber, which may, for convenience of nomenclature be termed a stopper gasket. Said gasket is engaged between flanges 6 and 7, of the nozzle 4, so as to be held against relative displacement when compressed into fluid tightness for seating either within the mouth of the priming cock 8 of the motor cylinder of which a portion is shown at 9 in Fig. 1, or in any suitable opening provided for this purpose. Such fluid tightness may be readily maintained during injection simply by exerting slight downward pressure upon the syringe in the grasp of one hand while the other hand is employed in actuating the handle 3. As a precaution against possible accidental splashing or rejection of the liquid through back pressure created during rapid vaporization of the liquid in the course of injection, I have provided a guard 10, which surrounds and overhangs the lip about the mouth of the priming cup and which in the present instance is formed as an integral part of the stopper gasket 5.

In use, the syringe is first applied to the priming cock and firmly held in the manner already explained. The cock is next opened and the charge of the scavenging fluid injected by moving the actuating handle 3 downward. After the desired amount has been introduced into the cylinder, the syringe is held in place until the cock 8 is closed. A sufficient time period is then allowed to elapse for dissolving or disintegrating the carbon deposits, which, after the motor is started are ejected with the exhaust.

The modification shown in Figs. II, III, and IV, is similar to the first described form except for the addition of means whereby the syringe may be detachably secured to the priming cock so that both hands may be entirely free for actuating the syringe during the operation of injecting. This means is in the form of a toggle mechanism comprising links 15, 15, pivoted at dia-

metrically opposite points to a metallic cap piece 16 wherein the stopper gasket 17 is housed, and a bale 18 which is fulcrumed to the lower ends of said links and provided with toggle extensions 19, 19, in turn pivoted at 20—20 to a bifurcated attaching member 21, adapted to engage behind or beneath the cup or head 22, of the priming cock. A handle extension 23, of the member 20, facilitates engaging of the latter with a cup in the course of attaching the nozzle. A cursory examination of Fig. II, will show that the toggle mechanism is effective in compressing the stopper gasket 15 to the requisite extent in effecting and maintaining a fluid tight seal during injection, in addition to firmly holding the syringe in place. Release of the toggle mechanism is effected by drawing the bale 18 upward until the links 15, 15, are swung to the side of the pivot center 20—20, of the toggles 19—19, opposite to that shown, whereafter the syringe may be readily withdrawn.

A further departure of the modified form 25 of my invention over the first described em-

bodiment will be observed in that the integral protective splash guard of the stopper gasket is here omitted and its function transferred to the extended or enlarged portion 24 of the cap piece 16.

Having thus described my invention, I claim:

The combination with a nozzle for syringes of a resilient tapered tip adapted to seat against the mouth of a priming cup of an engine, a cap-piece within which the tip is housed, said cap piece having an expanded lower part constituting a surrounding splash guard, and toggle clamp mechanisms associated with the cap piece whereby said tip may be detachably secured to the priming cup with the resilient tip compressed to maintain a fluid tight seal.

In testimony whereof, I have hereunto signed my name, at Philadelphia, Pennsylvania, this 6th day of December, 1921.

DONALD MCKNIGHT HEPBURN.
